United States Patent Office.

P. DAVIS, OF NEWPORT NEWS, VIRGINIA.

Letters Patent No. 79,324. dated June 30, 1868.

IMPROVEMENT IN LETTER-POUCHES.

The Schedule referred to in these Letters Patent and making part of the same.

TO ALL WHOM IT MAY CONCERN:

Be it known that I, P. DAVIS, of Newport News, in the county of Warwick, and State of Virginia, have invented a new and improved Letter-Pouch; and I do hereby declare that the following is a full, clear, and exact description thereof, which will enable others skilled in the art to make and use the same, reference being had to the accompanying drawings, forming part of this specification.

This invention relates to a new and improved letter-pouch, and it consists in forming the same with a flap, and a band or a slit to receive the end of the flap.

The exterior of the pouch is ruled or lined off at equal distances apart, and the several spaces are numbered, and the names of the places or addresses written or printed upon them.

In the accompanying sheet of drawings—

Figures 1 and 2 are side views of my invention, the two sides of the same pouch being shown.

Similar letters of reference indicate corresponding parts.

The pouch A is made, of oblong rectangular form, out of strong paper, well pasted at its bottom and sides, or where the edges are lapped. One side of the pouch is longer than the other, to admit of a flap being made to fold over the open end of the pouch, and a transverse slit, a; is made in the short side of the pouch to receive the end of the flap, (see fig. 1.)

Both sides of the pouch are ruled or lined off, and numbered, and each space has an address printed or written upon it, as shown clearly in fig. 2

The letters put into the pouch correspond to the addresses on the exterior, and as they are taken from the pouch, (those of each address,) the corresponding address on the exterior is scored out or marked off.

Having thus described my invention, what I claim as new, and desire to secure by Letters Patent, is—

A letter-pouch, having its exterior lined or ruled off, with addresses printed or written thereon, substantially as shown and described.

The above specification of my invention signed by me, this first day of May, 1868.

P. DAVIS.
